UNITED STATES PATENT OFFICE.

DAVID MILNE, OF ANSONIA, CONNECTICUT, ASSIGNOR, BY MESNE ASSIGNMENTS, TO FARREL-BIRMINGHAM COMPANY, INCORPORATED, OF ANSONIA, CONNECTICUT, A CORPORATION OF CONNECTICUT.

ROLL FOR CANE MILLS, CRUSHERS, AND THE LIKE.

Application filed September 14, 1925. Serial No. 56,300.

This invention relates to rolls particularly adapted for use in juice expressing cane mills or crushers, which are often used in advance of such mills. It may also be noted that my 5 improvements are not necessarily limited to rolls for use in this relation only, but are applicable to rolls of other type wherein it is desired to improve the capacity of two or more cooperating rolls to draw into 10 the bite between them the material to be acted upon.

When rolls of this character are newly manufactured and incorporated in a machine, the surface of the rolls is usually more or less 15 smooth, and for this reason there is inclined to be a slippage between them and the material upon which they are acting or which passes therebetween. In other words, a pair of such rolls will not have, to as great 20 a degree as is desirable, the property of biting into or taking hold of the material to be acted upon and drawing it into the roll bite. This is true of the rolls used in cane mills at 25 the present time, notwithstanding the fact that such rolls are usually provided with a series of alternate peripheral grooves and ridges, the rolls being usually so placed that the rib or ridge of one roll will enter to some extent the groove in the cooperating roll. 30 As a result when new rolls are installed in a crusher or in a three-roll mill, it is common practice to open up the rolls until their surfaces have been roughened or pitted by the 35 action of the juice or cane passing therethrough. The rolls can then be closed down to their normal positions where they will operate with the greatest efficiency and at highest capacity. The time required for this roughening process by the action of the cane 40 juice is from one to two weeks, and in the meantime, a considerable loss in the operation of the mill results, as during this time, the mill will not, of course, have operated at its greatest efficiency.

45 One object of my invention, therefore, is the provision of a roll for cane mills, crushers or the like, having its surface so scored or roughened that it will bite into, and draw into the roll bite, the cane or material to be acted upon, without substantial slippage.

Another object of my invention is to provide rolls for cane mills or the like, such that when such rolls are new and are first installed the rolls of the mill may be initially

closed down and run at the proper distances 55 from each other, so that no loss in efficiency will result from the substitution of a new roll for an old one.

A still further object of my invention is the provision of a pre-pitted or pre-scored roll 60 for cane mills, crushers or the like having regularly and uniformly arranged pits or depressions.

Another object is to provide a sugar cane roll having its surface pressed in or dented at 65 regular intervals on the V-shaped ribs thereof so as to produce efficiently acting pits or depressions for gripping the cane.

To these and other ends the invention consists in the novel features and combination 70 of parts to be hereinafter described and claimed.

In the accompanying drawings:

Fig. 1 is a diagrammatic view of a common 75 form of cane mill installation;

Fig. 2 is an elevational view of a roll, embodying my invention;

Fig. 3 is a fragmentary enlarged elevational view of a portion of the surface of the roll, and

Fig. 4 is a sectional on line 4—4 of Fig. 2.

In Fig. 1 of the drawings, I have shown a cane mill installation embodying two pairs of crusher rolls 10 and 11, and three sets of three-roll cane mills 12, 13 and 14. It will 85 be noted that the rolls of both the crushers and the three-roll mills are provided with peripheral grooves and ridges, the rolls being so arranged relatively to each other that in some instances, and especially in the case of the 90 three-roll mills, the ridges of one roll will enter to some extent the grooves of a cooperating roll. The arrangement shown, is merely by way of example, however, and is deemed to be a conventional form of cane mill 95 installation, and it is not to be inferred that my invention is necessarily restricted to rolls used in the precise combination shown.

My improved roll shown at 15, in Fig. 2, may be used either in the preliminary crushers or in the three-roll mills, and as previously stated, may also be used in other relations where rolls of this character are desired. The roll is provided with a number of peripheral grooves 16, between which are ridges 100 17, the ridges as well as the grooves being substantially V-shaped in cross section so that the apex of a ridge on one roll may enter a 105

groove in the adjacent roll when the center distance of the rolls are such that this is possible.

As such rolls have been made in the past, 5 their surfaces are comparatively smooth except for these grooves and ridges, or in other words, the sides of the grooves and ridges are comparatively smooth and as a result, when the cane is fed to such rolls, there is a 10 tendency for them to slip over the cane stalks instead of drawing such stalks into the roll bite, due to their smooth surfaces. As has already been stated, this results in a loss of efficiency when new rolls are used until such 15 rolls become sufficiently roughened so that they bite into the cane to a sufficient extent to exert a drawing or pulling action thereon.

The rolls constructed according to my invention, are provided with a number of 20 scores or pits 18 in the form of recesses formed in the walls of the grooves and ridges. While these recesses or pits may be varied considerably in form, they are according to the preferred embodiment illustrated and shown especially in Fig. 4, of 25 substantially hour-glass shape, having enlarged or flaring end portions 19 and 20, and restricted intermediate portions 21. The pits are elongated in shape and extend substantially over the entire wall 22 of the groove and especially to the apex 23 of the ridges, as shown in Fig. 3, the upper ends of these 30 pits intersecting the ridges, the result being that the ridge presents a sinuous or wavy 35 outline. While as stated, these pits extend substantially over the greater part of the wall of the groove, they may terminate a short distance from the bottom thereof, as shown in Fig. 4.

40 As shown, these pits are formed substantially radially of the axis of the roll, and while the two corresponding pits on the opposed walls of each groove are set substantially opposite each other, they are preferably staggered with the pits of the adjacent 45 grooves so that the pits upon one side of each of the ridges are staggered with those formed on the other side thereof.

The pits are preferably formed in the 50 surface of the rolls by a mechanical process so that they may be made with a degree of evenness and regularity and may be staggered on opposite sides of the ridges, as explained, although it will be understood that the location 55 of these pits may be varied as well as their shape or number, without departing from the principle of the invention. The pits will not interfere in any way with the operation of the roll scrapers, so that the result is that 60 with rolls embodying my invention there is a positive feed of the cane thereto without appreciable slippage, and a mill may be used to capacity immediately that a new roll is installed, thus representing a great saving over 65 the prior practice when the operation of the

mill was required for a week or more with the rolls opened up before they could be closed down, and operated at capacity load.

As shown in Fig. 3, when the pits upon one side of a ridge intersect the ridge line or apex at one side thereof, and are staggered with the pits intersecting the ridge line upon the opposite side, this line or apex presents a wavy appearance and will itself be roughened to some extent so as to increase the 75 drawing action of the rolls upon the cane.

Briefly, the mechanical process for forming the pits will be that of rolling or knurling depressions in the roll surface. The pits or depressions will be created by forcing in 80 or denting the metal of the roll surface at points in regular succession, so that the elongated depressions are equidistantly arranged around the circumference of the roll, preferably in a multiplicity of annular 85 series, these annular series being staggered, as before described, although this is not always necessary. The bottoms of the pits or depressions are curved by preference, and, preferably also, the pits are rather shallow 90 and yet fairly wide, as shown in Fig. 3.

While I have shown and described a preferred embodiment of my invention, it will be understood that it is not to be limited to all the details shown, but is capable of modification and variation within the spirit of the invention and within the scope of the appended claims.

What I claim is:-

1. A roll for cane mills or the like, having 100 formed in its surface a plurality of grooves, and V-shaped ridges between said grooves, and elongated pits formed on the walls of the ridges and extending downwardly from the apices thereof, said pits being in staggered 105 relation on opposite sides of the ridge.

2. A roll for cane mills or the like, having 110 formed in its surface a plurality of grooves, and ridges between said grooves, having sharp apices, the walls of said ridges having elongated pits formed therein, the walls of 115 said ridges being unbroken between said pits, said pits intersecting at their upper ends the apices of the ridges and extending downwardly therefrom.

3. A roll for cane mills or the like, having 120 formed in its surface a plurality of grooves, and ridges between said grooves, having relatively sharp apices, the walls of said ridges having elongated pits formed therein, the walls of 125 said ridges being unbroken between said pits, said pits intersecting at their upper ends the apices of the ridges and extending downwardly therefrom, the longer dimension of said pits being substantially perpendicular to the axis of the roll.

4. A roll for cane mills or the like, said roll having upon its surface a plurality of peripheral grooves and ridges, the ridge lines of said ridges being recessed on the opposite 130

sides thereof at staggered points to give said lines a sinuous shape, the recesses terminating short of the groove bottoms.

5. A roll for cane mills or the like, said roll having upon its surface a plurality of peripheral grooves and ridges, the ridge lines of said ridges being recessed on the opposite sides thereof at staggered points to give said lines a sinuous shape.

10 6. A roll for cane mills or the like, said roll having upon its surface a plurality of peripheral grooves, and V-shaped ridges having sharp apices between said grooves, the walls of said ridges having recesses formed therein, the recesses extending to and intersecting the ridge line and being staggered on opposite sides thereof, whereby the ridge line presents a sinuous shape.

7. A roll for cane mills or the like, said roll 20 having upon its surface a plurality of alternating peripheral grooves and ridges, the walls of said ridges having formed therein elongated pits extending from the ridge line downwardly and intersecting this line upon 25 opposite sides at staggered points along its length.

8. A roll for cane mills or the like, having upon its surface a plurality of alternating grooves and ridges, the walls of said ridges 30 having elongated pits formed therein, the longer dimension of said pits lying substantially at right angles to the axis of the rolls,

and said pits being of substantially hour-glass shape, with flaring ends and a restricted intermediate portion.

35

9. A roll for cane mills or the like, having upon its surface a plurality of alternating grooves and ridges, the walls of said ridges having elongated pits formed therein extending from the ridge line downwardly, the 40 longer dimension of said pits lying substantially at right angles to the axis of the rolls, and said pits being of substantially hour-glass shape, with flaring ends and a restricted intermediate portion, the upper flar- 45 ing ends thereof intersecting the ridge line at staggered points upon opposite sides thereof.

10. A cane roll having V-shaped ribs with knurled sides, the recesses so formed extending to the ridge line of the ribs, the surface of the ribs between said recesses being preserved in its original form.

50

11. A sugar cane grinding roll having V-shaped grooves therein, the side walls of said grooves being knurled to form depressions serving as pits to increase the biting action of the roll on the cane, said depressions terminating short of the groove bottoms, the depth of said pits being shallow 60 with respect to the width thereof.

In witness whereof, I have hereunto set my hand this 5th day of September, 1925.

DAVID MILNE.
